UNITED STATES PATENT OFFICE.

ALBERT P. LEE, OF CHICAGO, ILLINOIS, ASSIGNOR TO LEE TRAILER & BODY CO., OF CHICAGO, ILLINOIS.

DUMPING VEHICLE.

1,412,121.

Specification of Letters Patent. Patented Apr. 11, 1922.

Original application filed May 2, 1919, Serial No. 293,202. Divided and this application filed November 3, 1919. Serial No. 335,437.

To all whom it may concern:

Be it known that I, ALBERT P. LEE, a citizen of the United States, residing at Chicago, in the county of Cook and State of Illinois, have invented a certain new and useful Improvement in Dumping Vehicles, of which the following is a full, clear, concise, and exact description, reference being had to the accompanying drawings, forming 10 a part of this specification.

My invention relates to dumping vehicles and more particularly to a dumping vehicle which is provided with a hopper adapted to roll from charge receiving position toward the rear end of the vehicle and discharge its load over the upper end of the hopper.

It is an object of my invention to provide a dumping vehicle of the character set forth 20 which has a hopper of large capacity, which hopper is provided with a substantial bearing portion in contact with the frame of the vehicle so as to provide a rigid and substantial support for the hopper.

It is a further object of the invention to provide a drop frame vehicle having a hopper positioned on the lower portion of the frame which hopper is adapted to roll along the frame and discharge its load beyond the rear end of the frame.

It is a further object of the invention to provide means for securely maintaining the hopper in its charge receiving position which means may also control the movements of the 35 hopper while it is rolling toward its discharge position. In some cases it may be desired to discharge only a portion of the load in the hopper. In such cases means are necessary to prevent the hopper from 40 rolling completely to its discharge position.

The controlling means I have devised enables me to effectively control the movements of the hopper and to hold it in any desired position.

Other objects of the invention will be apparent from the detailed description of the device disclosed in the drawings wherein I have disclosed one form of my invention, which form is the best known to me at the 50 present time. However, it is to be understood that by this specification and the accompanying drawings I do not intend to limit myself to the specific construction disclosed as modifications of the specific construction may be required in the manufac-

ture thereof or may occur to those skilled in this art. The real nature and scope of the invention disclosed is to be determined from the claims appended to this specification.

The same reference characters have been used to designate the same parts throughout the several views of the drawings in which—

Fig. 1 is a longitudinal vertical section 65 of my improved dumping vehicle;

Fig. 2 is a plan view of the vehicle with the hopper removed (but indicated in dotted lines) in order to disclose more clearly 70 the structure beneath it;

Fig. 3 is a vertical section taken on line 3—3 of Fig. 2 and showing a portion of the controlling mechanism for the hopper;

Fig. 4 is a section taken from line 4—4 of 75 Fig. 2;

Fig. 5 is a section taken on line 5—5 of Fig. 3.

In the drawings I have disclosed a trailer frame work comprising side members 10 which have raised portions 11 at their forward ends and drop or depressed portions 12 at their rear ends. The side members 10 are preferably formed from the single plate which is cut to the desired shape and is then reinforced along its edges by means of angle 80 bars which are securely riveted thereto as shown in my copending application, Serial 293,202, of which this case is a division. The side members 10 are securely and rigidly connected together by means of channel cross 85 members 13, 14, 15, 16, 17 and 18. At the forward corners of the frame work thus formed I provide brace plates 19 and 20. The construction just described provides a rigid rectangular frame work upon which 90 the hopper, later to be described, is mounted. 95

Extending across the frame work between the members 13 and 14 is an I-beam 21 which forms a rigid support for a king bolt 22 which is adapted to engage a suitable opening provided in a turn table 23 carried by a front truck structure 24. This truck structure is supported by suitable springs 25 which are connected to the front axle 26 in any desired manner. The front axle is provided with wheels 27.

Extending longitudinally of the vehicle frame work and rigidly connected to the cross members 14 and 15 are channel members 28, 29 and 30 which channel members, 110

together with the side member 10 shown near the bottom of Fig. 2, form suitable and rigid supporting means for the hopper controlling mechanism which will be described later.

5 Between the raised portion 11 and the depressed portion 12 of the frame work there is a downwardly inclined surface 31 against which the front wall of the hopper will rest when the hopper is in normal position. The 10 depressed portion 12 is provided with a horizontal bearing portion 32 and beyond this bearing portion is an inclined portion 33 down which the hopper may roll to its discharge position. At the end of the inclined portion 33 I provide hook members 34 which provide pivot means for the hopper as it swings to its discharge position.

The hopper which rests upon the depressed portion of the frame work comprises vertical 20 side walls 35, an inclined front wall 36, a flat and substantially horizontal bottom wall 37 and an inclined rear wall 38. On the outside of the hopper I provide bearing rails which have inclined portions 39 extending 25 along the front wall 36 of the hopper. The rails have horizontal portions 40 which are secured to the flat bottom portion 37 of the hopper, and beyond these portions the rails are curved as shown at 41 in the drawings.

30 These curved portions of the rails are adapted to engage the inclined runways 33 so that the hopper may roll down the runways with a smooth rolling movement. Beyond the curved sections 41 are straight

35 portions 42 of the rail which strengthen the inclined rear walls 38 of the hopper and form suitable means to which the hopper holding mechanism may be secured. Adjacent the meeting point of the curved sections 41 and the straight portions 42 the

40 hopper is provided with pivot pins 43 which are adapted to engage the hook members 34 when the hopper reaches the end of the runways 33. After the pins 43 have engaged

45 the hook members 34 the hopper will swing around the pins as pivots until the load is completely discharged. This swinging movement is limited by the controlling mechanism which will later be described. At the

50 rear end of the hopper I provide a spreading attachment 44 which may be used for regulating the discharge of the hopper contents over the rear edge of the hopper. This arrangement is necessary when the hopper is used as a spreading device. As this feature forms no part of the present invention it is not disclosed in detail.

The rear end of the frame work is provided with longitudinally extending members 45 which are suitably secured to the cross channels 17 and 18 as shown in Fig. 2. The members 45 constitute suitable means to which springs 46 and 47 may be secured. These springs extend transversely 65 of the vehicle as shown in the drawings and

their ends are suitably attached to the rear axle 48 which axle in turn carries the wheels 49. While this method of attaching the rear wheels has been disclosed in the drawings, it will be apparent that other means and arrangements of springs may be used if desired. 70

In order to maintain the hopper in its normal charge receiving position and to control its movements during the dumping operation the following mechanism is used. Secured to the rear cross member 18 are brackets 50 which brackets provide suitable means for pivotally supporting toggle members 51. There are two of these toggle members as will be clear from Fig. 2, one positioned adjacent each side of the frame. These toggle members 51 extend upwardly and have their upper ends pivotally secured to a pivot rod 52. Pivotally connected at 53 to brackets carried by the hopper and associated with the rail portions 42 are upper toggle members 54 which have their lower ends pivotally connected to the rod 52. The members 51 and 54 provide a toggle mechanism which is shown in its extended position in Fig. 1 of the drawings. When the rod 52 is permitted to move to the right in Fig. 1 the toggle mechanism is collapsed and the hopper is permitted to roll down the runways 33. In order to prevent the toggle members from swinging past their normal position shown in Fig. 1 I provide extensions 55 on the toggle members 54 which extensions are provided with fingers 56 100 adapted to engage the lower toggle members 51 as shown in Fig. 1. The fingers 56 prevent the toggle members from swinging beyond their normal position shown in Fig. 1. 95

Pivotally connected to the rod 52 adjacent each of the toggle members is a link 57 and the links 57 are connected by means of a rod or bail member 58 which bail has secured thereto one end of a cable 59. This cable extends forwardly over a pulley 60 carried by the cross member 17 and then passes under a second pulley 61 suitably connected to the cross member 16. From this point the cable passes upwardly and over pulley 62 carried by the hopper adjacent the upper edge of the front wall 36, and then passes downwardly and around a winding drum 63 which is rigidly secured to a stub shaft 64 as will be more apparent from Fig. 3 of the drawings. The 110 stub shaft 64 has its bearings in the longitudinally extending members 28 and 29. The drum 63 has an enlarged hub portion 65 which prevents longitudinal movement of the shaft 64. Secured to one end of the 115 shaft 64 by means of the key 66 is a clutch element 67 formed with an extending clutch portion as shown in Fig. 2 of the drawings. The clutch element 67 is adapted to engage a clutch element 68 which is splined to the 120

125

130

shaft 69 by means of the key 70. The shaft 69 is in alignment with the shaft 64 as will be clear from Fig. 3 of the drawings. In order to connect and disconnect the clutch element 68 from the element 67 I provide a clutch operating member 71 which is supported in brackets 72 and 73 carried by the frame work. The clutch operating member is provided with a handle 74 by means of which it may be easily operated. When the handle 74 is pulled outwardly it serves to disconnect the clutch element 68 from the element 67. When the handle is moved inwardly the reverse operation takes place.

Keyed to the shaft 69 by means of the key 75 is a bevel gear 76 which meshes with a bevel gear 77 secured to the shaft 78 which shaft is positioned at right angles to the shaft 69. Also secured to the shaft 78 is a worm 79 which meshes with a worm wheel 80 keyed to the shaft 81. The worm and worm wheel are suitably enclosed in a housing 82' which forms bearings for the inner end of the shaft 81 as shown in Fig. 4. The shaft 81 extends through a side member 10 and its outer end is provided with a squared shank 82 to which a crank or other operating member may be attached for controlling the movements of the hopper. The housing 82' referred to is cast in two parts as shown in Fig. 4 of the drawings and these parts are held together by bolts or rivets as shown in Fig. 4. The clutch operating member 71 has its inner end turned downwardly as shown at 83 in Fig. 3 and this end is forked in order that it may engage a groove in the clutch element 68 as shown in Fig. 3.

The raised portion 11 of the frame work supports an auxiliary hopper 84 which hopper may be used for any desired purpose but is preferably used for carrying tools, etc., which are used on the work for which the vehicle is intended.

From what has been described above the construction of my device will be apparent. The operation will also be apparent from the preceding descriptions, but a brief description of the operation will be given here. When the hopper is loaded it has a tendency to roll down the runway 33 toward its discharge position. This movement is prevented by the toggle members 51 and 54 which are maintained in the position shown in Fig. 1 by means of the cable 59. When it is desired to discharge the load from the hopper the operator places a crank or other operating member on the squared shank 82 of the shaft 81. The shaft 81 and worm wheel 80 will then be rotated in the proper direction. This will permit the worm 79 to turn under the weight of the hopper. It will be understood that the hopper due to its shape and the load contained therein exerts a constant pull on the cable 59. As

the shaft 81 is turned the worm 79 is released and the gears 76 and 77 and the shafts 64 and 69 are turned under the action of the hopper drawing on the cable 59. If it is desired to permit the hopper to roll at once to its complete discharging position the operator will pull out on the handle 74 to disconnect the clutch element 68 from the clutch element 67. This frees the drum 63 and the hopper is free to roll down the inclined runways 33 and pivot around the pins 43 as pivots. The length of the cable will be such as to limit this swinging movement of the hopper. When the clutch elements are left in engagement as shown in Fig. 3, the hopper may be stopped in any desired position on the runways 33. The worm 79 and worm wheel 80 constitute a locking connection so that the shaft 81 cannot rotate due to the pull on the cable 59 and the hopper can roll down the runways only when the shaft 81 is rotated by the operator.

From what has been described the nature of my invention will be readily apparent and it will be also apparent that many modifications may be made within the scope of the appended claims.

Having thus described my invention what I claim as new and desire to secure by United States Letters Patent is:

1. A device of the character described including a runway, a rolling hopper adapted to roll thereon between a charge carrying and a discharge position, link mechanism at one end of said hopper for controlling the position of said hopper, a flexible tension member for controlling said link mechanism, and means whereby said member also controls the other end of said hopper. 105

2. A device of the character described including a runway, a rolling hopper adapted to roll thereon between a charge carrying and a discharge position, link mechanism at one end of said hopper for controlling the position of said hopper, a flexible tension member for controlling said link mechanism, means whereby said member also controls the other end of said hopper, and self-locking means for controlling said member. 110

3. A device of the character described including a runway, a rolling hopper adapted to roll thereon between a charge carrying and a discharge position, link mechanism at one end of said hopper for controlling the position of said hopper, a flexible tension member for controlling said link mechanism, means whereby said member also controls the other end of said hopper, self-locking control means for controlling said member, and means for connecting or disconnecting said member from said self-locking control means. 115

4. A device of the character described including a runway, a rolling hopper adapted 120

- to roll thereon between a charge carrying and a discharge position, link mechanism at one end of said hopper for controlling the position of said hopper, a flexible tension member for controlling said link mechanism, means whereby said member also controls the other end of said hopper, and a worm and worm wheel for controlling said member.
- 10 5. A device of the character described comprising a frame work having an inclined runway, a hopper adapted to roll down said runway from a charge carrying to a discharge position, toggle members for controlling the position of said hopper on said runway, a cable connecting the said toggle members and extending beneath said hopper toward the forward end of the said frame work and means carried by said frame work 15 for winding up or releasing said cable to control the position of the hopper on the runway.
6. A device of the character described comprising a frame work, a hopper adapted to roll on said frame work from charge carrying to a discharge position, toggle members for holding said hopper in charge carrying position, a pulley on the frame work beneath the hopper, a pulley carried 20 by said hopper, a winding drum on said frame work and a cable extending from said toggle members over said pulley to the winding drum for controlling the position of the hopper on said frame work.
- 30 7. A device of the character described comprising a runway having a flat portion, a hopper having a flat portion adapted to rest on the flat portion of said runway when in load carrying position, said hopper being 35 adapted to roll automatically from load carrying to discharge position, toggle links for holding said hopper in load carrying position, and means for unlocking said
- 40

toggle links and controlling the movements of said hopper on said runway, said means comprising a flexible member having an end portion thereof connected to said toggle links, an intermediate portion thereof engaging said hopper, and the other end portion thereof wound on a drum and means for controlling the movements of said drum to wind said flexible member thereon or unwind it therefrom.

8. A device of the character described comprising a runway having a flat portion, 55 a hopper having a flat portion adapted to rest on the flat portion of said runway when in load carrying position, said hopper being adapted to roll automatically from load carrying to discharge position, toggle links 60 for holding said hopper in load carrying position, and means for unlocking said toggle links and controlling the movements of said hopper on said runway, said means comprising a flexible member having an end 65 portion thereof connected to said toggle links, at the joint thereof, an intermediate portion thereof passing over a pulley mounted on said hopper, and the other end portion thereof wound on a drum and means for controlling the movements of said drum to wind said flexible member thereon or unwind it therefrom.

9. A device of the character described comprising a runway, a hopper adapted to 75 roll automatically on said runway from load carrying to discharge position, toggle mechanism for locking said hopper in load carrying position, and means for unlocking said toggle mechanism, said means controlling 80 the movements of the hopper on said runway.

In witness whereof, I hereunto subscribe my name this 31st day of October, A. D., 1919.

ALBERT P. LEE.
